United States Patent Office

Des. 218,845
Patented Sept. 29, 1970

218,845

WATCH BRACELET OR SIMILAR ARTICLE

Ananta Uengsakul, Bangkok, Thailand, assignor to Stelux Manufacturing Company, Ltd., San Po Kong, Kowloon, Hong Kong, a corporation of Hong Kong

Filed July 3, 1968, Ser. No. 12,608

Term of patent 14 years

Int. Cl. D11—01

U.S. Cl. D45—4

FIG. 1 is a plan view of a watch bracelet showing my new design.

FIG. 2 is a side elevation thereof taken along the line 2—2 of FIG. 1.

The bottom surface of the watch bracelet is of conventional appearance.

I claim:

The ornamental design for a watch bracelet or similar article, substantially as shown and described.
